CLAIM

The ornamental design for an elastic strap for a charm with a slot, as shown and described.

DESCRIPTION

FIG. 1 is a perspective view of an elastic strap for a charm with a slot depicted on an equestrian riding crop in accordance with the present invention;

FIG. 2 is a perspective view of an elastic strap for a charm with a slot in accordance with the present invention;

FIG. 3 is a front view of the elastic strap for a charm with a slot in accordance with the present invention;

FIG. 4 is a top view of the elastic strap for a charm with a slot in accordance with the present invention;

FIG. 5 is a right side view of the elastic strap for a charm with a slot in accordance with the present invention;

FIG. 6 is a left side view of the elastic strap for a charm with a slot in accordance with the present invention;

FIG. 7 is a rear view of the elastic strap for a charm with a slot in accordance with the present invention;

FIG. 8 is a bottom view of the elastic strap for a charm with a slot in accordance with the present invention;

FIG. 9 is a perspective view of the slot of a charm for the elastic strap for a charm with a slot in accordance with the present invention;

FIG. 10 is a right side view of the slot of a charm for the elastic strap for a charm with a slot in accordance with the present invention; and,

FIG. 11 is a left side view of the slot of a charm for the elastic strap for a charm with a slot in accordance with the present invention.

The broken lines in the Figures show portions of the elastic strap for a charm with a slot and form no part of the claimed design.
